UNITED STATES PATENT OFFICE.

MORRIS F. BENTON, OF PLAINFIELD, NEW JERSEY, ASSIGNOR TO AMERICAN TYPE FOUNDERS COMPANY, OF JERSEY CITY, NEW JERSEY, A CORPORATION OF NEW JERSEY.

DESIGN FOR A FONT OF PRINTING-TYPE.

No. 39,325.

Specification for Design.

Patented May 26, 1908.

Application filed February 24, 1908. Serial No. 417,623. Term of patent 14 years.

To all whom it may concern:

Be it known that I, MORRIS F. BENTON, a citizen of the United States, residing at Plainfield, in the county of Union and State of New Jersey, have invented a certain new, original, and ornamental Design for a Font of Type, of which the following is a specification.

The drawing shows a plan view of a font of printing type embodying my new design.

I claim:—

The ornamental design for a font of printing type as shown.

MORRIS F. BENTON. [L. s.]
